UNITED STATES PATENT OFFICE

GEORGE A. GILLEN, OF BRONX, NEW YORK, ASSIGNOR TO OAKES PRODUCTS CORPORATION, OF NORTH CHICAGO, ILLINOIS, A CORPORATION OF MICHIGAN

AUTOMATIC STARTING SYSTEM AND CONTROL FOR HYDROCARBON ENGINES

Application filed December 26, 1931. Serial No. 583,322.

My invention relates to an improved starting system and control for hydro-carbon engines in which the starting motor is automatically switched into circuit when the ignition switch is closed and is automatically disconnected from circuit when the engine has been properly started thereby, and is automatically reconnected in circuit to re-start the engine in case the engine should accidentally stop.

In starting systems, as for example in automotive vehicles, where the source of current supply, such as a battery, is of limited voltage, there must be considerable current flow in order to deliver sufficient power to the starting motor to start the engine. The switch members and contacts of the circuit controlling switch for the starting motor are therefore subjected to heavy current flow, and the resulting arcing will soon roughen the contact surfaces so that the current flow through the resulting restricted current paths will fuse the metal of the contacts, and so-called freezing together of the contacts will result and this is particularly disadvantageous in electro-magnetically operated switches as the contacts will not separate after opening of the energizing circuit for the switch and the starting motor will remain in circuit after the engine has been started and is running at a high speed and this may result in serious damage to the motor or the engine. An important object of my invention is therefore for the provision of means, in connection with an electro-magnetically operated switch for the starting motor circuit, which will become automatically effective to cause relative movement of the switch contacts for separation thereof as soon as the energizing circuit for the electromagnetic switch is opened.

A further object of the invention is to provide improved means dependent for its operation upon the operation of the engine, and adapted to close the switch energizing circuit and render the contact releasing and separation means ineffective for starting of the engine by the starting motor, and to open the energizing circuit for separation of the switch contacts and to render the contact releasing means effective for separation of the

contacts in case of freezing of the contacts or any other condition which would tend to prevent separation of the contacts in the ordinary manner.

A further object of the invention is to provide electromagnetically controlled means for releasing the contacts, and a circuit for such means partly controlled by the relative movement of the contacts.

A still further object is to provide electro-magnetic means for controlling the separation of the contacts and a circuit for such means conjointly controlled by the relative movement of the contacts and by the running of the engine.

Still another object is to provide governor means connected either directly or indirectly with the engine shaft, and switch means controlled by the governor means to close the energizing circuit for the electromagnetic starting switch when the engine is at rest, and to open the energizing circuit and close the contact releasing circuit after the engine has been started but the contacts have not separated to open the starting circuit.

Another object is to provide a switch of the solenoid type in which relatively movable core members are surrounded by an energizing winding and form the terminals of the starting motor circuit to be shifted into contact to close such circuit when the energizing circuit is closed, together with means automatically controlled to effect relative rotational movement of said core members to release them from freezing engagement or other conditions which would prevent their separation after opening of the energizing circuit.

The above specifically referred to and other features of the invention are incorporated in the structure shown on the drawings, in which drawings

Figure 1 is a more or less diagrammatic illustration of my improved electromagnetic starting switch and the governor and switch mechanism controlled thereby, and connecting circuit and other controlling switches, the starting circuit controlling switch being shown in vertical diametral section;

Figure 2 is an end view of the starting circuit controlling switch; and

Figure 3 is a section on plane III—III of Figure 1;

Figure 4 shows an alternative position and the governor controlled switch.

Describing first the electromagnetic switch, it comprises a spool-shaped frame 10 of insulating material on which is applied the energizing winding or solenoid 11. Secured to one end of the spool is a bracket 12 by means of which the switch structure may be supported as for example on the starting motor diagrammatically shown and indicated by the numeral 13. A stationary cylindrical switch terminal or contact member 14 extends concentrically in one end of the bore of the spool 10 and has the post 15 extending therefrom through an opening 16 in the bracket 12, a nut 17 engaging the post to thus secure the terminal member, insulating washers 18 being preferably interposed so as to insulate the terminal member from the bracket.

Extending into the other end of the bore of the spool 10 is the cylindrical switch terminal member 19, the terminal members being preferably of copper or other good current conducting metal. The terminal member 19 is surrounded by a sheath or sleeve 20 of good magnetic material such as Swedish iron which forms an armature or core for the solenoid 11, this sleeve being secured to the member 19 and extending only along the inner part thereof.

The inner end of the terminal member 19 is of frusto-conical shape to form a frusto-conical contact surface 21. The inner end of the stationary terminal member 14 is countersunk to provide the conical surface 22 parallel with the frusto-conical surface 21 on member 19 so that the end of the member 19 may intimately engage with the end of the member 14. A compression spring 23 seated in the pocket 24 in the member 14 extends outwardly into engagement in the recess 25 formed at the apex of the member 19 and is insulated from this member by the insertion of a lining 26 in the recess of insulating material as for example so called bakelite, this spring tending to hold the switch terminal members normally separated and out of electrical contact. When the member 19 is in its outer position the magnetic shell 20 thereon is displaced from the magnetic center of the energizing coil 11 but upon current flow through the coil the shell will be shifted inwardly and the terminal member 19 will be brought into electrical engagement with the stationary member 14 to close the starting motor circuit. This circuit extends from the battery 27 through the conductor 28 to a terminal post 29 mounted on the cylindrical flange 30 extending from the outer end of the spool 10, the post being connected by a flexible connector 31 with the switch terminal member 19. The stationary member 14 is connected by a conductor 32 with one terminal

of the starting motor 13 whose other terminal is grounded, and one side of the battery 27 is also grounded so that when the switch is energized and the terminal members 19 and 14 brought into engagement, the starting circuit is closed and the starting motor operates.

Upon opening of the energizing circuit, the spring 23 will tend to separate the switch terminal member 19 from the terminal member 14, but such separation may be prevented by the freezing of the terminals or other reasons.

The releasing means for the switch terminals comprises an electromagnet 33 mounted within the outer head of the spool 10 at one side of the bore thereof, and an armature bar or lever 34 extending crosswise of and secured to the outer end of the movable switch terminal member 19. The lever may be secured in cross passage 35 in the member 19 and when this member is in its outer or circuit-opening position the lever will be outwardly displaced from the end 36 of the electromagnet 33, and a spring 37 extends from the opposite end of the lever and is anchored to the spool head and tends to hold that end of the lever against a stop post 38 with the lever away from the magnet core in the direction of the magnet axis, so that normally the end of the lever is displaced both axially and laterally from the electromagnet core. Upon energization of the switch coil and inward movement of the switch terminal member 19 to close the starting circuit, the armature lever will be moved inwardly with its end in front of the electromagnet core but still displaced therefrom by a gap. However, if the electromagnet 33 should now be energized the lever 34 will be swung against the pull of the spring 37 and the switch terminal member 19 will be axially rotated relative to the stationary terminal 14 and if these members have been frozen or held together such relative turning will cause shearing action between the members to release them from each other so that the spring 23 may function to separate the members and shift the member 19 outwardly.

The armature lever 34 carries a contact plate 39 which is insulated therefrom, and mounted on the head of the spool 10 is a flexible contact arm 40. When the switch terminal member 19 is shifted inwardly to close the starting circuit, and the electromagnet 33 is not energized, the contact plate 39 will come into engagement with the contact arm 40 to close at that point an energizing circuit for the electromagnet 33, and if the electromagnet is now energized and the lever 34 is swung, the contact 39 will be disconnected from the contact arm 40 to open the energizing circuit, but, upon the opening of the circuit and the de-energization of the mag-

net, the spring 37 will swing the lever 34 back to re-engage its contact 39 with the arm 40, and thus, so long as the switch terminal member 19 is in its inner position and the electromagnet 33 is energized, the lever 34 will be repeatedly swung and the terminal member 19 repeatedly axially oscillated so that, if separation of the terminal members is not fully effected after the first rotation of the member 19, rotation of the member will be repeated until separation is accomplished and the spring 23 may function to fully separate the terminal members. The relative movement of the terminal member thus controls at one point the energization of the releasing magnet 33.

The releasing circuit is controlled at another point by a switch mechanism A automatically controlled by a governor mechanism B which is permanently connected either directly or indirectly with the shaft of the engine with which the starting system is associated. The switch A comprises a switch lever 41 connected by conductor 42 with the contact 43 of the switch C, the switch lever or blade 44 being connected with the positive terminal of the battery 27. A contact 45 of the switch A is connected by conductor 46 with one terminal of the energizing winding 11 of the electromagnet starting switch, the other terminal of the winding being connected by conductor 47 with ground. The contact 48 of the switch A is connected by conductor 49 with the contact plate 39 on the armature lever 34, and the contact 40 is connected by conductor 50 with one terminal of the electromagnet 33 whose other terminal is connected by conductor 51 to ground. Thus upon engagement of the switch blade 44 of the switch C with the switch contact 43, and engagement of the switch blade 41 of the switch A with its contact 45, current will flow from the battery through the energizing winding 11, and when the switch blade 41 is shifted to the contact 48, this energizing circuit will be opened and the release circuit will be closed through the electromagnet 33 if the switch terminal member 19 remains in its inner or circuit closing position. When the switch terminal member 19 is in its outer position the circuit will be opened as the contact 34 on the armature lever is disconnected from the contact arm 40 as has already been explained.

The switch C has other contacts 52 and 53 both connected with one terminal of the primary winding 54 of a suitable ignition coil for providing ignition current for the engine. When the switch blade 44 connects with the contact 43 it is also in connection with the contact 52 so that the ignition coil is switched into circuit at the same time that the energizing circuit for the starting electromagnet switch is connected with the battery. Upon

swing of the switch blade to the contact 53, the contacts 43 and 52 will be disconnected and only the ignition coil will be in circuit for the ordinary starting of the motor. In other words, by one setting of the switch C closure of the ignition circuit will be automatically followed by starting of the engine, and in another setting of the switch only the ignition circuit is closed and the engine must be started in some other manner.

Describing now the governor mechanism B and its automatic control of the switch A, the governor may be mounted on the shaft 55 of the generator G, or on any other available shaft or member which is rotated when the engine is running. The governor mechanism is more or less diagrammatically illustrated and as shown, it may comprise a collar 56 rigidly secured on the shaft 55 and a hub or sleeve 57 shiftable on the shaft but held by a spline 58 to rotate with the shaft. At its outer end the hub 57 has the flange 59 for cooperating with the switch A. Pivoted to the fixed collar 56 are the levers 60 terminating at their outer ends in governor balls 61, these levers being connected by links 62 with the sleeve 57 so that as the balls are swung outwardly by centrifugal action the sleeve will be shifted on the shaft 55. A spring 63 tends to hold the ball levers inwardly with the sleeve abutting against the collar 56, this being the position when the engine and consequently the shaft 55 are at rest.

The switch blade 41 of the switch structure A has the horns or extensions 64 and 65 between the ends of which is received the flange 59 on the sleeve 57. An arm 66 extending outwardly between the horns is connected by a spring 67 with the bracket 68 extending from the frame of the generator G and serving as a mounting for the operating parts of the switch mechanism A, the anchorage point of the spring 67 on the bracket being directly below the pivot point 69 of the switch blade 41 so that as the blade swings to either side of the spring axis its further movement will be a snap action. Stops 70 and 71 are provided on the bracket 68 for limiting the swing of the switch blade, the blade at the end of its swing being either in engagement with the contact 45 or the contact 48 to which reference has already been made.

Describing now the operation of the system, if it is desired to use the automatic starting feature, the ignition switch C, which is normally open, is moved into engagement with the contacts 43 and 52. Battery current then flows through the primary side of the ignition winding for the ignition of the engine, and battery current also flows through the switch blade 41, contact 45 and through conductor 46 and the energizing winding 11 of the electromagnetic switch. The switch terminal member 19 is then drawn inwardly into engagement with the stationary terminal 14

to close the starting circuit for the starting motor 13 and the engine is turned for starting. The inward movement of the terminal member 19 also brings the armature lever 34 into operative position relative to the electromagnet 33 and the contact 39 on the armature lever comes into engagement with the contact arm 40 to close at that point the energizing circuit for the electromagnet 33.

10 The turning speed of the engine by the starting motor is small compared to the running speed of the engine, and the governor weight and spring are adjusted so that during turning of the engine by the starting motor there will not be sufficient movement of the sleeve 57 for actuation of the switch blade 41 of the switch A. As soon, however, as the engine has been started and has acquired sufficient speed, the governor will shift the sleeve 57 far enough so that the cooperation of the flange 59 with the horn 65 of the switch blade 41 will swing the switch blade beyond the neutral line of the spring 67 and then the switch blade is quickly snapped into engagement with the contact 48; such movement first opening the energizing circuit of the electromagnet switch and then closing the energizing circuit for the electromagnet 33 at a second point. Upon de-energization of the electromagnet starting switch the spring 23 should shift the terminal member 19 outwardly away from the stationary member 14 to break the starting motor 30 circuit. Such outward movement of the member 19 would break the energizing circuit of the electromagnet 33 by disengagement of the contact 39 from the contact arm 40. However, if the movable terminal member 19 has become frozen or stuck to the stationary member 14 so that the spring 23 cannot cause separation, then the energizing circuit of the electromagnet 33 remains closed and the armature lever 34 will be attracted by the electromagnet and swung to cause rotation of the terminal member 19 relative to the stationary member 14, and such movement will break loose and release the terminal member 19 so that it may be shifted to its outer or circuit opening position. When the armature lever is swung to rotate the member 19 the contact 39 is disconnected from the contact arm 40 and the spring 37 will swing the lever away from the electromagnet core end to re-engage the contact 39 with the arm 40, and if after the first oscillation of the member 19 it has not been fully released from the member 14 it will be given another oscillation. Then after complete release and outward shift of the member 19 the armature lever will be shifted outwardly with the member 19 to open the energizing circuit for the electromagnet by the separation of the contact 39 from the contact arm 40, the energizing circuit however remaining closed at the engagement of the switch blade 41 with the contact 48 of the

switch A. While the engine is running for transmission power delivery, the electromagnetic starting switch remains open but should the engine at any time stop unknown to the driver, the governor will come to rest and the sleeve 57 will be shifted to swing the switch blade 41 back into engagement with the contact 45, which movement causes complete opening of the energizing circuit for the electromagnet 33 and reestablishment of the energizing circuit for the electromagnet switch and the starting motor is thus automatically reconnected for restarting of the engine. Of course, if the driver opens the ignition switch the engine will come to a stop and the switch A will be set for operation of the electromagnetic starting switch as soon as the ignition switch is reclosed.

The horns 64 and 65 of the switch blade 41 are preferably dimensioned so that they will be in contact with the flange 59 of the sleeve 57 only until the switch blade has been shifted through the neutral line of the spring 67 in either direction, and after setting of the switch the flange 59 will not engage with the horns, friction being in this way avoided.

If the driver does not desire to use the automatic starting, he may set the switch C to connect the blade 44 only with the contact 53 so that only the ignition coil will be in circuit and the engine can then be started by cranking or in any other manner. An insulated knob 72 may be provided at the outer end of the movable switch terminal member 19 so that the member 19 may be shifted manually to close the starting circuit, such manual starting being desirable when inspection or repairs are being made.

As has been pointed out, the adjustment of the governor is such that, during turning of the engine by the starting motor, the sleeve 57 will not be shifted sufficiently to actuate the switch A. When the engine has been started the sleeve 57 will be shifted into cooperation with the switch blade 41 to cause disconnection of the starting switch circuit, and the arrangement and adjustment is such that, even though the engine slows down to a slow idling speed, the sleeve 57 will not return a sufficient distance to swing the switch blade 41 beyond the neutral line, and it is only when the engine fails and comes to a stop that there is sufficient return movement of the sleeve 57 to swing the switch 41 past the neutral line for snap action thereof to reclose the starting switch energizing circuit, and operation at any time of the starting motor while the engine is running, will be prevented.

As changes and modifications may be made in the construction and arrangement and operation without departing from the scope of my invention, I do not desire to be limited to the exact structure and arrangement shown except as is specified in the appended claims.

I claim as my invention:

1. In an electrical system, a solenoid coil, an energizing circuit therefor, switch means controlling said energizing circuit, circuit terminals extending into opposite ends of said 5 coil and means adapting said terminals for movement into engagement with each other when said coil is energized, means tending to separate said terminals, electromagnetic releasing means and a circuit therefor, means 10 for closing said releasing circuit at one point when said terminals are moved into engagement, said switch means being adapted in one position to close the energizing circuit and open said releasing circuit at another point 15 76 and adapted in another position to open the energizing circuit and close the releasing circuit at such point and thereby fully close said releasing circuit upon failure of said terminals to separate when said energizing circuit 20 is opened, said electromagnetic means being connected to cause relative axial rotational movement of said terminals for release thereof and separation, and a working circuit controlled by said terminals. 25
2. In an electrical system, the combination of a solenoid coil, an energizing circuit therefor, terminals surrounded by said coil, a working circuit controlled by said terminals, means whereby said terminals are relatively moved in said coil toward each other to close said working circuit upon closure of said energizing circuit, means tending to move said terminals apart to open said working circuit when said energizing circuit is 30 80 opened, and electrical means independent of said coil operable to cause relative movement of said terminals in a direction different from that of movement of the terminals directly away from each other whereby upon adhesion 35 of said terminals to each other after opening of the energizing circuit, said terminals will be released from each other for separation by said separating means. 40
3. In an electrical system, the combination of an electromagnetic switch comprising a coil, an energizing circuit for said coil, an armature movable in response to current flow through said coil, circuit terminals engaged by the movement of said armature, a working 45 90 circuit controlled by said terminals, means tending to separate said terminals upon interruption of current flow through said coils, and means automatically operable to cause shearing action between said terminals to 50 assist said separating means in separating said terminals upon cessation of current flow through said coil. 55
4. In an electrical system, the combination of an electromagnetic switch comprising a 60 coil and an armature movable in response to current flow through said coil, a current supply circuit for said coil, a working circuit, switch contacts for said working circuit adapted to be engaged by the movement of 65 said armature to close said working circuit, 75 means tending to separate said contacts, and electromagnetic means associated with said contacts for causing shearing action between them to assist separation thereof by said separating means upon cessation of current flow 80 through said coil. 85
5. In an electrical system, an electromagnetic switch comprising a solenoid and a core member shiftable therein in response to current flow therethrough, a current supply circuit for said solenoid, a contact member movable with said core, a companion contact member in the path of the movable contact member, a working circuit controlled by said contacts to be closed when said contacts are 90 brought together, means tending to separate said contacts, a releasing electromagnet and a circuit therefor, an armature lever having operative connection with said core and means for closing the energizing circuit of 95 said releasing electromagnet whereby said armature lever is contracted and said core and the contact thereon rotated to effect shearing action between said contact members for release thereof from each other and separation thereof by said separating means. 100
6. In an electrical system, the combination of an electromagnetic switch comprising a solenoid and a core shiftable therein in response to current flow therethrough, a current supply circuit for said coil and controlling means for said circuit, a contact movable with said core, a companion contact in the path of said movable contact for engagement thereby, means tending to separate said contacts, a working circuit controlled by said contacts to be closed when said contacts are in engagement, a releasing electromagnet, an armature lever having operative connection with said core and normally displaced from 105 the magnetic field of said releasing magnet but shifted into such field when said core is moved to engage said contacts, an energizing circuit for said release electromagnet, and switch means operative to open said coil circuit and close said electromagnet energizing circuit, closure of said electromagnet circuit causing attraction of said armature lever and rotational movement of said movable contact for shearing action between said contacts 110 to effect release of said contacts for separation thereof by said separating means. 115
7. In an electrical system, an electromagnetic switch comprising a solenoid and a core movable therein in response to current flow 120 therethrough, a current supply circuit for said solenoid, a contact movable with said core and a companion contact in the path thereof for engagement thereby upon current flow through said solenoid, means tending to 125 separate said contacts, a working circuit controlled by said contacts, a releasing electromagnet, an armature lever having operative connection with said core and normally displaced from the magnetic field of said releas- 130

ing electromagnet but shiftable into such field when said contacts are brought into engagement by said core, an energizing circuit for said releasing electromagnet, normally open switch means adapted to close said electromagnet energizing circuit at one point when said contacts are brought together by said core, and switch means operative to open said coil circuit and close said electromagnet energizing circuit at another point for complete closure of said electromagnet circuit, closure

of said electromagnet circuit resulting in attraction of said armature lever and rotational movement of said core and contacts to effect shearing action between said contacts in case they have become stuck together, whereby to release said contacts from each other for separation by said separating means.

In testimony whereof I have hereunto subscribed my name at Chicago, Cook County, Illinois.
